UNITED STATES PATENT OFFICE

JOHN WIEDEMANN, OF CLEVELAND, OHIO, ASSIGNOR TO AMERICAN STOVE COMPANY, OF ST. LOUIS, MISSOURI, A CORPORATION OF NEW JERSEY

HINGE CONSTRUCTION

Application filed November 4, 1930. Serial No. 493,374.

This invention relates to improvements on hinge constructions, of the type particularly adapted for use on doors mounted on heated objects, such as the ovens of ranges 5 or the like.

The object of the invention is the provision of a hinge of the concealed type which does not have in its makeup any springs with the result that it is particularly adapted for use on doors which are subjected to heat.

A further object of the invention is the provision of a hinge for a door which will hold the door in practically any position 15 and will prevent the door from dropping and thus eliminates strain and possible breakage, which would be caused by the dropping of the door.

Another object of the invention is the provision of a door hinge having numerous specific and improved features of construction bringing about a novel and improved operation.

In the drawings—

Figure 1 is a view in front elevation showing the application of the improved hinge to the oven doors of a range, a portion of the figure being broken away and shown in vertical section.

Fig. 2 is a view in end elevation, a portion of the figure being shown in vertical section.

Fig. 3 is a detail view illustrating the stop for the door when in its open position.

Fig. 4 is an enlarged detail view illustrating the several positions of the hinge when the door is in several positions between its open and closed positions, a portion of the view appearing in dotted lines.

Fig. 5 is a strung-out perspective view, the parts going into the make up of the door and the hinge being shown in unassembled relation, a portion of the view being shown in section.

Fig. 6 is a front view of a modified form of the hinge applied to a door, the door and a portion of the door frame being shown in vertical section.

Referring now to the drawings, A is a rectangular frame of a U-shape in cross-

section which forms the marginal edge of the openings into the cooking and broiling ovens of a range. A cross member B divides the frame into two parts so as to define two openings which are closed by the doors C and D, the doors for the baking and broiling ovens respectively.

One leg of the frame A is designated as 7, and the other leg designated as 8 is of a configuration to form a seat 9 for the oven 60 and broiler doors.

The cross-member B is approximately U-shaped in cross-sectional configuration, being composed of a vertical wall 10, a narrow top horizontal leg 11 and a wide horizontal leg 12. The vertical wall 10 is longer than the cross-member and has its ends 13 bent to extend in the same direction as the horizontal legs 11 and 12. This cross-bar is secured in place by having its ends 13 welded 79 to the inner sides of the legs 8 of the frame A, with the result that the cross-member extends rearwardly towards the oven.

At the points where the ends 13 of the cross-bar are welded the frame legs 8 are 75 cut out, as indicated at 14. This cut out portion permits the free passage of the square shaft 15, which is positioned in the U-shaped cross-bar and extends through the squared openings 16 in the bar ends 13, 80 which openings register with the cut-out portions 14 in the frame legs.

It is intended that the shaft 15 be fixed against rotation and to this end a lock 17 is provided. This lock has a squared opening 18 which goes over the end of the square shaft 15 at a point exterior of the opening 16 of the cross-bar. This lock 17 is secured to the leg 8 of the frame by a suitable bolt which passes through the openings 19 and 20 provided in the frame leg and lock respectively.

The doors C and D are identical in construction except as to dimensions. These doors comprise a front panel 21 and a lining 22 having inturned marginal edges 23 and 24, which edges telescope when the two parts of the door are assembled. This construction leaves between the main panel and the lining of the door a space which is of a depth 100

equal to the width of these marginal edges. At their lower corners the door panel and the door linings are provided with cut-out portions. The cut-out portion of the door 5 panel is indicated at 25 and of the linings at 26. In its face adjacent its cut-out portion 25 the door panel is provided with an outward bulge 27.

The door hinges are designated as an 10 entirety by the letter E and it is to be understood that there are two of these hinges for each door. These hinges are of a U-shape and comprise the legs 28 and 29. The end 15 of the leg 28 is thickened to form a hub-like portion 30 having therethrough an opening 31 for the reception of the shaft 15. The other leg 29 of the hinge is tapered as to thickness clearly indicated in Fig. 5 of the drawings. At the point 32 this leg of the hinge 20 is of normal thickness, but from this point to the end of the leg the thickness of the material making up the hinge tapers so that at its lowermost end 33 it is quite thin.

Suitably secured upon the top of the shaft 25 15, at points adjacent its ends are rounded lugs or cams 34.

The hinges are made up of material which has resilient qualities and in assembling the structure the hinges are slid onto the shaft 30 15 and then the shaft 15 positioned in the U-shaped cross-bar and secured against rotation. The ends 33 of the hinge legs 29 are positioned behind the rounded legs or cams 34. By reference to Fig. 4, it will be 35 seen that positioning the parts in this manner puts the hinge under tension due to the fact that the legs 28 and 29 are held out of alignment. This distortion of the hinges has a tendency to hold them towards the 40 oven or stove and to hold the doors in closed position, because the doors are carried by the hinges, as will now be described.

The hinge legs 28 are provided with threaded openings 35 and 36 and the door 45 linings are provided with bolt openings which register therewith and the linings are fastened to the hinges by suitable bolts which are indicated at 37 in Fig. 1 of the drawings. In fastening the linings to the hinges the 50 hinges are on the inner side of the linings and the hinges are now completely enclosed and positioned within the space between the door-lining and the door panel by placing the panel in telescopic relation with the lining and securing the marginal edges of the lining and panel together by suitable bolts passing through the plurality of openings 38. With the door lining and panel in place 55 it will be seen that the hub-like ends 30 of the hinges extend outwardly through the cut-out portions 26 at the lower corners of the lining and the cut-out portions 25 at the lower corners of the panel extend around the shaft 15, while the bulged portions 27 60 at the lower corners of the panel provide an

accommodating space for the hub portions 30 of the hinges.

As has been pointed out, the hinges are under tension even when the door is closed so as to hold the doors tightly on their 70 seats to prevent heat escapement from the oven. This tension of the hinges also prevents longitudinal movement of them upon the shaft 15.

The doors, as is usual in ranges, open 75 downwardly and as illustrated in Figs. 3 and 4 of the drawings, it will be seen that the greater the downward movement of the door the greater the distortion out of alignment of the legs 28 and 29 of the hinges, 80 due to the movement of the ends 33 of the hinge leg 29 over the rounded lug or cam-like member 34.

Fig. 4 illustrates in full line the hinge position when the doors are closed. Reading 85 this figure towards the left the next dotted position illustrates the position of the hinge when the door is partly open, and when the parts are in this position the spring tension is sufficiently strong to cause the hinges to 90 return the door to its closed position. The remaining dotted position of the parts illustrates the positions of the hinge when the door is completely open. From the intermediate position to the completely open position 95 the door must be moved against the tension of the hinges with the result that the doors cannot drop and, consequently, possible breakage on account of the strain created by the dropping of the door is eliminated.

This hinge construction is such that the door will remain in any set position between the intermediate and fully open positions. Once the tension upon the lower ends of the 105 hinge legs 29 is at a point back of the center of the shaft 15, the door will automatically assume a closed position. When the tension upon the ends of the hinge legs 29 is in front of the center of the shaft 15, 110 the door will remain in any set position.

From the foregoing it will be seen that the hinge is completely concealed in the space between the door lining and door panel with the exception of the hub-like portion 30. 115 It will be further seen that the construction is extremely simple and that the door front panel can be removed without removing the door. The construction further eliminates all ordinary springs which is highly 120 desirable as it has been found that ordinary springs in hinge constructions for doors utilized on heated objects or members will not last as the springs rapidly lose their tension when operated in heated zones. The 125 present hinge utilizes tension, but the hinges are sufficiently heavy to withstand any heat which may get to them in their protected position.

At its bottom the frame A is provided 130

with a cross-bar similar to the cross-bar B and the hinge and door construction of the door D is exactly similar to that described for the upper door C of the oven.

5 In Fig. 6, a slightly modified form of the invention appears wherein it will be seen that any possible longitudinal movement of the hinges is guarded against. Here the rounded lugs or cam-like members, which 10 are designated at 40, are provided with up-standing ears 41, and the ends 33 of the hinge legs 29 travel and are guided between these lugs. To further guard against longitudinal movement of the hinges the ends of 15 the hinged legs 29 are forked and carry lugs 42 which travel the outer faces of the cam-ears 41. Thus the cam ears 41 travel in the spaces 43 at each side of the leg end 33 between the leg end and the leg lugs 20 42.

In the range construction the floors of the oven are in the same horizontal plane with the top legs 11 of the cross-bars B, with the result that when the doors are 25 open, the door linings are in the same plane with the oven bottoms.

To assure this alignment and to provide a limited movement of the doors, the construction is such that when the doors are 30 completely open the faces 44 (see Fig. 3) abut the ends 45 of the door seat 9, at the point where the door seat and the leg 8 of the frame A are cut-out at 14.

Viewing the stove from the front, it will 25 be seen that no part of the hinge or door-supporting means is visible to the eye. The square shaft which is in reality the pintle of the door is concealed between the door front panel and lining as is also the hinge 40 itself. By attaching the door lining to the hinge leg carrying the hub the lining leg is free to be sprung by the shaft cam. When the doors are closed, they are contained com-

pletely within the frame A, so that the inside faces of the door linings are in contact with the door seats and the door front panels are flush with the faces of the frame A, all of which lends a pleasing appearance to the 70 range construction.

Having thus described my invention what I claim and desire to secure by Letters Patent is:

1. An improved construction, comprising 75 a hinge member made of a piece of material capable of being flexed and formed into two legs in separated relation, said hinge legs movably mounted, one leg supporting a door and the other leg free to be flexed, a cam arranged in the path of travel of the free leg, said cam normally causing a flexing of the free leg and further causing a continuing and increased flexing of the free leg upon an opening movement of the door, 80 means on said cam for preventing longitudinal movement of the free leg in respect to the cam, and means on the free leg co-acting with the cam for further preventing longitudinal movement of the member in respect 85 to the cam.

2. An improved construction, comprising 90 a hinge including a continuous piece of material capable of being flexed and formed into two leg portions in separated relation, 95 said legs movably mounted and means for moving them, one leg supporting a door and the other leg free to be flexed, the free leg in engagement with a rounded cam causing 100 a flexing of this hinge leg, upon a movement of the door said free hinge leg travelling over said cam, ears carried by said cam forming a guide for the free leg over the cam, and ears carried by the free leg 105 and positioned beyond the ends of the cam for preventing longitudinal movement of the hinge legs in respect to the cam.
